UNITED STATES PATENT OFFICE.

ALBERT KRASA, OF CHICAGO, ILLINOIS, ASSIGNOR TO BATES VALVE BAG COMPANY, OF CHICAGO, ILLINOIS, A CORPORATION OF WEST VIRGINIA.

HEMMING MACHINE AND PROCESS OF FORMING BAG TUBING.

Application filed March 16, 1922. Serial No. 544,127.

My invention relates to a hemming machine and the process of hemming and forming bag tubing, and has for its object the provision of a machine with which bag tubing may be formed having one longitudinal seam, the edges of the cloth being inwardly turned before sewing and the seam being sewed along the opposed inwardly turned edges, and through them, making four thicknesses.

The machine is particularly adapted for use with bag forming machinery wherein a tube is formed from a roll of bagging material and the tube is either continuously or after a storage interval formed into bags by a process which consists in closing the bottom of the tube, charging material therein and cutting and severing the lower portion of the tube when thus filled. Other purposes of my invention will appear from time to time in the course of the specification.

I illustrate my invention more or less diagrammatically in the following drawings, wherein:

Figure 1 is a plan view of the sewing portion of my invention;

Figure 2 is a section on the line 2—2 of Figure 1;

Figure 3 is a section on the line 3—3 of Figure 2;

Figure 4 is a section on the line 4—4 of Figure 2;

Figure 5 is a section on the line 5—5 of Figure 2;

Figure 6 is a plan view of the hemming element;

Figure 7 is a section on the line 7—7 of Figure 5;

Figure 8 is a section on the line 8—8 of Figure 5;

Figure 9 is a section on the line 9—9 of Figure 5;

Figure 10 is a section on the line 10—10 of Figure 5;

Figure 11 is a section on the line 11—11 of Fig. 1;

Figure 12 is a plan view of the supply

roll and fabric feeding portion of the machine;

Figure 13 is a side elevation of the structure shown in Figure 12;

Figure 14 is a section on the line 14—14 of Fig. 13;

Figure 15 is a section on the line 15—15 of Figure 13.

Like parts are indicated by like indicating symbols throughout the drawings and specifications.

A is a roll of material to be used from which may be fed a flat strip of material A¹. The roll lies on a horizontal circular rotating shelf A² which is pinned upon the vertical rotating shaft A³ which is mounted on any suitable framework A⁴ supported for example by the legs A⁵. The bottom of the shaft A³ rotates in ball bearings A⁶, associated with any suitable constant frictional brake A⁷ adapted automatically to prevent any abnormal speed of rotation of the shaft. The top of the shaft is tapered at A⁸ and indented to receive a pointed bolt A⁹ which is adjustable in the hinge member A¹⁰ on the vertical channel arm frame A¹¹ which is joined to the base by the plate A¹². Spaced outwardly from the frame A¹¹ is a vertical guide B, illustrated as a tube, which is joined to the frame member A¹¹ at top and bottom by adjacent spacing elements B¹ slotted at B² to receive the adjusting bolts B³. Thus the guide may be adjusted to fabric and tubes of various sizes.

The fabric strip A¹ passes about the vertical guide B and is then folded along its central axis to form a doubled strip C which passes over any suitable horizontal guide C¹ illustrated as a hook shaped metallic member mounted on the bracket arm C². The doubled tube C passes across the support C¹ and its adjacent free edges then pass into a hemmer plate D which will later be described in detail. The effect of this plate is to turn each edge of the cloth inwardly to produce a pair of opposed inwardly turned flaps or edges as shown in Figure 10. The tube edges then pass between a pair of

knurled rollers E E¹³ lying in opposition one above and one below the tube and rotating in opposite directions to draw the edge of the tube between them and through the hemmer plate. The roller E is keyed on the shaft E¹ in any suitable bearings E² E³ and has at its end a pinion E⁴ in mesh with the helical gear E⁵ on a vertical shaft E⁶ which is supported in some suitable ball bearing E⁷ at its bottom and has adjacent its bottom the worm E⁸ driven by the worm E⁹ on a drive shaft E¹⁰ which is connected by the pulley E¹¹ and belt E¹² with any suitable power source. The bearings E² and E³ of 15 the shaft E¹ are mounted on the bracket F which is pivoted at its ends upon the shaft F¹ which in turn is secured at its ends to the upwardly projecting frame members F² F² and suitably supported upon the base of the 20 machine as for example by the screw plate F³. The roller E¹³ is mounted on the shaft F⁴ which rotates in the members F⁵ F⁵. At the outer end of F⁴ is a pinion F⁶ in mesh with the second helical gear F⁷ on the shaft 25 E⁸. The roller E is normally drawn down upon the roller E¹³ by the adjustable spring G which is adjustably secured to the base of the machine, at its lower end, as for example by the bolt G¹ and nut G² and at its 30 top is secured in any suitable way to the bracket F. A pivoted cam element H is illustrated having a handle H¹, whereby the upper roller may be manually lifted from contact with the lower roller, if so desired. 35 A stop H¹⁰ limits the movement of the cam element as shown in Figure 4. Between the rollers and the sewing means, later to be described, lies the guide plate I having a portion I¹ folded over its base portion and 40 spaced apart therefrom sufficiently to admit the free passage of the requisite four layers of cloth. The guide plate is secured to the base of the machine as by a screw plate I². J is the usual form of presser foot mounted 45 on the presser shaft J¹, passing through the guide J² and movable on a vertical axis. Secured to the presser shaft is the outwardly bent arm J³ terminating in a hook J⁴ which underlies the shaft E¹ of the roller E. Thus, 50 if the presser foot J is lifted for the purpose of repair and adjustment, the roller E is automatically lifted from contact with its opposed roller E¹³. K is any suitable sewing needle mounted in the sewing shaft K¹, 55 which is driven from any suitable power source in the usual way.

Any suitable means, shown diagrammatically at J⁵, may be placed beneath the presser foot and needle to draw the fabric beneath the needle in the sewing operation. The mechanism may be, for example, the saw toothed reciprocating plate usually used for this purpose with sewing machines. The 60 sewed strip then passes over a rubber pulling 65 roll comprising a roller L and the rubber

surface L¹ thereupon, the roller L being mounted in the bearings L² L², and being normally rotated by a pulley L³ at the end thereof through a belt L⁴ driven from any suitable power source. To prevent the strip 70 from being pulled beneath the pulling roll, I provide the guard plate L⁵ the upper end of which is curved about to come in relatively close contact with the outer surface of the rubber roll. 75

Between the feeding rollers E E¹³ and the source of material is the hemmer plate D through which the folded fabric tube is drawn by the rollers E E¹³ to properly turn in the edges for the hemming or sewing 80 operation. This plate may be of any suitable form to perform the desired function, namely, to inwardly turn each of the opposed tube or strip edges, but I illustrate a preferred form wherein this function is satisfactorily performed. The outer edges of the hemmer plate, as shown in section in Figure 7 comprise two hem forming sections, the upper one comprising the opposed sides M¹ M² and the lower one comprising the opposed sides M³ M⁴, which may be, if desired, formed from one piece of spring sheet metal. It will be noted that as the material enters the hemmer plate the edges are slightly inwardly turned as at M⁵ M⁶. The sheet metal 90 bends M⁷ M⁸ have as function to support the parts of the hemmer and properly to space them. The hemmer is progressively flattened from the inlet portion to the outlet portion and Figure 8 illustrates a further section wherein by the curvature of the upper and lower portions the edges of the cloth have been brought about a relatively narrow arc and now lie within the folded tube body as at M⁹ M¹⁰. The cross section 95 of the hemmer at its inner end is shown in Fig. 9 where the folding is completed and the edges of the tubing have been inwardly folded at M¹¹ M¹² to the proper position for sewing. The opposed folded edges then pass through the rollers E E¹³ and through the guide plate I I¹ to the presser foot and needle. A renewable wire M²⁰ protects the corners of the hemmer plate at the point of greatest wear where the outer edges of the 100 folded fabric initially engage the hemmer at its outer angles as shown in Figures 5 and 6. 105

While I have illustrated a working device and one which is now being practically operated, it will be obvious that many changes might be made in the number, size, relation, and distribution of parts without departing from the spirit of my invention, and particularly I do not wish to limit myself to the specific form of hemmer and guide plates or the specific relation of such plates to the fabric drawing and fabric sewing mechanisms. 110

The use and operation of my invention 115 are as follows: 120

The material which is to be sewed into a tube is fed forward from the vertically supported roll about a vertical guide. The roll is supplied with an automatic friction brake which limits the speed of the feed and the vertical guide may be adjusted to bring the strip in proper position for folding and hemming various sizes of tube. The outer end of the tube is carried across the support C¹ as it is folded, and its opposed edges are fed into the hemmer plate, drawn between the pressure or feed rollers E E¹³, passed between the presser foot and the base of the machine and finally the sewed tube is carried forward over the rubber feeding roll. When the device is set in operation the opposed rollers E E¹³ are kept yieldingly in engagement with each other and their roughened or knurled surfaces draw the tube through the hemmer. As the tube is thus drawn the opposed edges are each inwardly folded. The tubing issues from the hemmer plate in proper position for the hemming or sewing operation. It passes through the guide plate I I¹ and under the presser foot beneath which reciprocates any suitable material feeding means. All the tension and force of drawing the material through the hemmer plate is provided by the knurled rollers and no strain is placed on the needles. This is important since by irregularities of the fabric or minor interruptions in its flow a strain would be put on the needle far greater than could be dealt with by the usual fabric feeding means in association with the sewing means. The result would be frequent breakage of the needle and stoppage of the whole process. This is prevented by the positive driving of the two feeding rollers. Only the edges to be hemmed pass through the hemmer, and the operation of the hemmer as well as that of the drawing rollers is irrespective of the size of the tube being formed, so that neither hemmer nor drawing device requires change to form tubes of different sizes.

However, because only the edges enter the hem turning device, these edges might enter varying distances, or escape entirely, if they were not properly guided and held in line. The guide roller B is adjusted so that the material will enter the hem turning device at the proper angle to insure turning the edges the amount desired without causing excessive wear on the plates or strain on the material. The brake is adjusted so as to insure that the material will not become slack, but will be held in the line to which it is guided by the roller B. The folded tube which is thus additionally compressed for the sewing, if such compression is necessary, passes through the earlier mentioned guide plate and to the sewing means, the fabric being fed forward as above described. The gathering of the material about the sewing

means is prevented by the frictional pulling roll, which is herein illustrated as a rubber roll, and the completed tube beyond such roll may be wound upon the storage spool, or it may be fed directly for use with packing machinery, or it can be otherwise packed or dealt with in any suitable manner.

I claim:

1. In combination, means for folding together the edges of a strip and turning said edges to form a hem, means contacting the edges only for drawing said edges through the hem-turning device, a sewing head having a presser foot and adapted to sew a seam longitudinally through the turned edges, and means connected to the presser foot whereby when the presser foot is raised the said drawing means is rendered inoperative.

2. In combination, means for folding together the edges of a strip of material and turning them inward to form a hem, a sewing machine having the usual feeding means and adapted to sew a seam longitudinally of the turned edges, and means between the edge turning device and the sewing machine contacting the edges only for drawing the edges through the edge turning device.

3. In combination, means for folding together the edges of a strip of material and turning them inward to form a hem, a sewing machine having the usual feeding means and adapted to sew a seam longitudinally of the turned edges, means between the edge turning device and the sewing machine contacting the edges only for drawing the edges through the edge turning device, and means contacting the full width of the folded strip for drawing the material away from the sewing machine.

4. In combination, means for folding together the edges of a strip of material and turning them inward to form a hem, a sewing machine having the usual feeding means and adapted to sew a seam longitudinally of the turned edges, a fixed roller beneath the turned edges between the edge-turning device and the sewing machine, a roller above the edges and said first named roller and movable in a vertical direction, a spring normally drawing the upper roller downward, said sewing machine having a presser foot, and an arm extending from the presser foot adapted to raise the upper roller, when the presser foot is raised.

5. In apparatus for forming tubes, a support adapted to support a roll of fabric with its axis vertical, a vertical guide adjustable horizontally and about which the fabric from the roll may be fed, a device beyond the guide for contacting only the edges of the fabric and turning them, a sewing machine adapted to sew together the turned edges, and means between the sewing machine and the edge-turning device for draw-

ing the fabric from the roll and through the device.

6. In apparatus for forming tubes, a roller for supporting the fabric, a tension device connected to the roller, means for drawing the fabric from the roll, means for folding the fabric along a median line, means there-

after contacting the edges of the fabric for turning them, and an adjustable bar parallel with said roller and adapted to guide the edges into the edge turning device.

Signed at Chicago, county of Cook, and State of Illinois, this 4th day of March, 1922.

ALBERT KRASA.
